UNITED STATES PATENT OFFICE

WILLIAM TURNER, OF PORTLAND, OREGON

WINDOW-SCREEN DEVICE

Application filed February 19, 1929. Serial No. 341,116.

This invention aims to provide novel means whereby closures of any desired kind, such as screens, may be mounted in a window frame for sliding movement, it being possible to remove and detach the screens or other closures readily and quickly.

In the drawings:—

Figure 1 shows in front elevation a window in which my invention has been embodied, parts being broken away, and parts being in section;

Figure 2 is a section on the line 2—2 of Figure 1;

Figure 3 is a section on the line 3—3 of Figure 1;

Figure 4 is a composite perspective view, showing the shoe and parts associated therewith.

The numeral 1 marks a frame including stiles 2 in which a window 3 is mounted in any desired way.

Closures, such as screen frames 4, are provided. One stile 5 of the screen frame 4 is provided with a fixed tongue 6 mounted to slide in a groove 7 formed in one of the stiles 2 of the window frame 1. The opposite stile of the window frame has a corresponding groove 8, there being one of the grooves 7 and one of the grooves 8 for each of the screen frames 4.

Any desired number of transverse bores 9 are formed in the stile 10 of the screen frame 4. Into the inner end of the bore 9 is threaded a tubular guide 11 having an enlarged head 12 which engages the inner surface of the stile 10.

The numeral 14 marks a U-shaped shoe mounted to slide horizontally in a recess 15 formed in the outer edge of the stile 10, the bore 8 communicating with the recess 15. The shoe 14 is carried by a stem 16, including an outer member 17 which is threaded into an inner member 18, the inner member 18 sliding in the guide 11, the stem 16 passing through the bore 9.

The inner member 18 of the stem 16 has a flattened end 19 received in a slot 20 formed in the head of a cam lever 21, the head of the cam lever being provided with an opening 22 adapted to receive a pivot element 23 car-

ried by the part 18 of the stem 16, the pivot element forming a fulcrum for the cam lever 21. The head of the cam lever is provided with straight parallel edges 24 and 25 which are disposed opposite each other, the edge 24 being nearer to the pivot element than is the edge 25. A compression spring 26 surrounds the stem 16. One end of the spring 26 engages the inner end of the guide 11, and the opposite end of the spring 26 bears against the shoe 14.

When the cam lever 21 is in such a position that the edge 25 bears against the end of the guide 11, the shoe 14 is retracted out of the groove 8, as shown in the lower left hand corner of Figure 1. When all of the shoes 14 are retracted, the screen frame 4 can be swung out of the window frame at one edge and the fixed tongue 6 can be removed from the groove 7, it being possible, thus, to detach the screen frame from the window frame. When, however, the edge 24 of the cam lever engages the guide 11, then the shoe 14 is advanced and is received slidably in the groove 8 to hold the screen frame 4 in the window frame 1 for sliding movement. The spring 26 prevents rattling and holds the lever 21 in place with either the edge 24 or the edge 25 engaged with the guide 11. Because the member 17 of the stem 16 is threaded into the member 18 of the stem, the device is adapted for use on screen frames the stiles 10 of which may be of different widths. The structure of course is capable of use in connection with closures other than screen frames.

Having thus described the invention, what is claimed is:—

1. In a device of the class described, a window screen adapted for mounting in the guide of a window frame, a shoe carried by the screen and slidable in the guide, a stem carrying the shoe, the stem comprising relatively adjustable parts which permit the length of the stem to be changed, and a cam lever on the stem, the cam lever cooperating with the screen to advance and retract the shoe with respect to the guide.

2. In a device of the class described, a window screen adapted for mounting in the

guide of a window frame, a tubular member in the screen, a shoe adjustable in the screen and slidable in the guide, a stem carrying the shoe and slidable in the tubular member, a 5 cam lever pivotally mounted on the stem and engaging the tubular member to advance and retract the shoe with respect to the guide, and a compression spring abutting against the shoe and against the tubular member.

10. 3. In a device of the class described, a window screen adapted for mounting in a window frame having a guide, the screen being provided with a recess in its outer edge, a U-shaped shoe having its ends slidable 15 in the recess, the shoe being received in the guide, a stem slidable in the screen and comprising members which are threaded together for adjustment, one of said members being secured to the intermediate portion of 20 the shoe, a cam lever pivotally mounted on the other of said members and coacting with the screen to retract the shoe, and spring means for advancing the shoe.

In testimony that I claim the foregoing as 25 my own, I have hereto affixed my signature.

WILLIAM TURNER.
